(57) **CLAIM**

The ornamental design for a whimsical garden stake, as shown and described herein.

DESCRIPTION

FIG. 1. Is a right side elevational view with left side elevational view being a mirror image of our whimsical garden stake;

FIG. 2. Is a front elevational view thereof;

FIG. 3. Is a rear elevational view thereof;

FIG. 4. Is a top plan view thereof; and,

FIG. 5. Is a bottom plan view thereof.

The stake is shown partially broken away in FIGS. 1-3 to indicate indeterminate length of the spring and shaft portions thereof.
